HENRY A. WISE WOOD, OF NEW YORK, N. Y., ASSIGNOR TO WOOD NEWSPAPER MACHINERY CORPORATION, OF NEW YORK, N. Y., A CORPORATION OF VIRGINIA

PRESS UNIT DRIVE

Application filed February 18, 1926, Serial No. 89,070. Renewed June 2, 1932.

This invention relates to the connection of several units of a printing press with the necessary folder or folders. The principal objects of the invention are to connect the units and folders in such a way as to reduce the expense of manufacture and maintenance; to avoid back lash in stopping and starting the presses by the elimination of the numerous gears now employed; and do away with vertical shafts.

Reference is to be had to the accompanying drawings in which

Fig. 1 is a plan of an embodiment of this invention which accomplishes the above named objects in the highest degree; and

Fig. 2 is a side view of the same.

When a number of press units are connected together it is customary to form the connection by means of a horizontal driving shaft which receives and delivers the power through a number of gears mounted on other horizontal and vertical shafts connected with the units. The horizontal driving shaft usually is located directly above or below the floor of the press and is driven by a motor placed adjacent thereto. When the motor is stopped or started, the several press units and folders are subjected to a certain amount of back lash or lost motion on account of these gears. This is multiplied by each set of gears used. Thus this effect is multiplied, which causes several difficulties, sometimes even the tearing of the paper.

The principal object of this invention is to avoid these difficulties and at the same time omit the cost of the gears and of their maintenance.

I will not describe the details of the press units any more than enough to show the application of this invention to one type thereof. It will be understood, of course, that the press units can be provided with inking mechanism, fresh roll supports, etc.

This type of press is simplified, as far as the drive is concerned, to as high a degree as is possible in a multiple unit press. This will be seen to be true, when it is pointed out that all the press units and folders are driven from a single main shaft on one of them, through an unbroken line of driving shafts

arranged end to end and in alignment and without any gears of any sort or other relatively movable parts for transmitting the power from one to another. These driving shafts, as well as the main shaft, are all located at the same level, or substantially so, namely the level of all the printing couples, so vertical shafts are eliminated with their gears.

In the form shown, the two units of the printing press are placed with their respective cylinders parallel to each other. The motor drive comprises the motor 10, chain 11 and power shaft 25. In this case, however, the power shaft is not one of the shafts of the press, or of any unit thereof, but extends along the whole combined machine. It delivers power through a single pair of beveled gears 26 to each of the driving shafts 27 of the several press units. It also delivers power through a corresponding pair of beveled gears 28 to the driving shaft 29 of the folder or system of folders. The driving shafts 27 are extended at one side in each case and they are all driven similarly from the main shaft 25.

In a press of this type the conventional method of connecting and driving the printing and folding elements shown, would require the use of at least seven shafts and twenty gears. The saving in the first cost, maintenance and back lash therefore is important.

Intermediate vertical shafts and gears are done away with, except that one pair of gears is used, but there is an important saving in the number of gears required for each machine. This reduces the expense and the amount of back lash.

Although I have illustrated and described only one form of the invention I am aware of the fact that modifications can be made therein by any person skilled in the art without departing from the scope of the invention as expressed in the claim. Therefore I do not wish to be limited to all the details of construction herein shown and described, but what I do claim is:

In a printing system, the combination with a plurality of press units arranged parallel to

- each other and registering with each other and a folding mechanism located at the end of the series so that the whole series is in alignment but the driving shafts of the press units and folder are all parallel, said driving shafts for the press units each being the shaft of one of the cylinders of the printing couple, and the folder having shafts perpendicular to the folder driving shaft for operating it but in the same horizontal plane, of a longitudinal main shaft extending along the system perpendicular to all of said driving shafts and in the same horizontal plane, and means connected with said main shaft for driving all the parallel shafts directly.
